UNITED STATES PATENT OFFICE.

WEBB JAY, OF CHICAGO, ILLINOIS.

VACUUM LIQUID-FEED DEVICE FOR INTERNAL-COMBUSTION ENGINES.

1,264,939.

Specification of Letters Patent. Patented May 7, 1912.

Application filed July 18, 1917. Serial No. 181,440.

To all whom it may concern:

Be it known that I, WEBB JAY, a citizen of the United States, residing at Chicago, in the county of Cook and State of Illinois, 5 have invented new and useful Improvements in Vacuum Liquid-Feed Devices for Internal-Combustion Engines, of which the following is a specification, reference being had to the accompanying drawings, forming 10 a part thereof.

The purpose of this invention is to provide an improved construction in vacuum fuel feeding devices for internal combustion engines. It consists in the elements 15 and features of construction shown and described as indicated in the claims.

In the drawings:—

Figure 1 is a vertical axial section of a device embodying this invention.

Fig. 2 is a section at the line, 2—2, on Fig. 1.

Two minor defects have been observed in the operation of vacuum fuel feeding devices of the general type which is illustrated in 25 the drawings, first, that the float which operates the pressure-alternating devices when made in the customary form as a completely inclosed sheet metal air-filled chamber is liable to have minute leaks undiscoverable by inspection, or to develop leaks after short use by slight corrosion at porous spots in the metal, by reason of which the float becomes filled with liquid and inoperative as a float; and second, that by reason of the 35 fact that atmospheric air is admitted directly to the vacuum chamber at intervals alternating with the suction, and that upon the recurrence of the suction after an interval of air admission, a considerable portion 40 of approximately pure atmospheric air is carried over into the manifold, there is liable to occur a corresponding alternation of suitably rich and unsuitably "lean" fuel-and-air mixture in the manifold, with slight diminution in the efficiency in the engine, because if the carbureter is adjusted to either condition, the adjustment will not be such as to produce the highest efficiency at the other alternating condition. The purpose 45 of this invention is specifically to overcome these two defects; and this is effected by using as a float or buoy in the vacuum chamber a downwardly-open or inverted cup, and causing the liquid supply to be discharged 50 into the chamber only under this cup or bell so that it reaches the remainder of the

chamber only by passing around the inner margin of the cup or bell, and rising outside thereof, in which process it entrains a certain amount of air, which in the process 60 of entrainment becomes charged with gasoline vapor; and so that a large proportion of the atmospheric air which is admitted to the chamber, passes into the bell around the lower margin thereof, taking some liquid in 65 the passage, and then out of the bell around the lower margin thereof, again taking some liquid. The total effect is that the air which can be drawn into the manifold from the vacuum chamber is substantially as highly 70 charged with gasoline as that which reaches the manifold through the carbureter, thus preventing the alternation of leanness and richness in the explosive mixture supplied to the engine.

It will be obvious of course that the danger of leakage of a closed float is obviated by the use of the open float or bell-shaped buoy, but there arises a different difficulty in the use of a bell or open-bottom float, consisting in that the liquid gradually absorbs the air from the float cavity and the float tends to become "water-logged," i. e., filled with liquid, and no longer operates as a buoy. The construction illustrated comprises features which obviate this difficulty.

In the drawings there is illustrated a familiar form of vacuum fuel feed tank, comprising a vacuum chamber, 1, reservoir, 2, into which the chamber, 1, discharges, and from which the carbureter, (not shown,) is supplied by the pipe, 3, the chamber, 1, being open to atmospheric pressure through the duct, 4, which connects with the air inlet passage, 5, which is controlled by the air valve, 6; suction being admitted from the manifold through the pipe, 7, and the port controlled by the valve, 8, said valves, 6 and 8, being connected for operation by the snap valve action whose operation is well understood, said action consisting of the levers, 10 and 11, connected by the spring, 12, stretched past their fulcrum, the lever, 9, fulcrumed on the chamber head having the buoy, 13, suspended from its free end, and intermediate its ends connected by the link, 15, with the lever, 11. The liquid fuel supply connection from the low tank, (not shown) from which the said supply is to be lifted by suction, is made by the pipe, 17, 110 leading in through the cap plate, 18, and continued by means of the pipe, 17a, which

extends down in the annular interval between the chambers, 1 and 2, and in through the wall of said chamber, 1, for discharging under into the downwardly-open cup-shaped buoy, 13.

Upon consideration of the structure shown, it will be understood that when the buoy is at the lowest position, the chamber, 1, has discharged its contents into the chamber, 2, to such an extent as to cause the buoy to descend to a position for closing the atmosphere valve, 6, and opening the suction inlet valve, 8, atmospheric pressure having up to that point been operating upon the liquid in the chamber, 1, the air will have passed around the lower margin of the buoy and up into the cavity thereof, and the liquid level will be nearly the same inside and outside of the buoy cavity, but being a little higher inside the cavity because a condition of partial vacuum has previously existed in that cavity. Upon the closing of the atmosphere inlet valve and the opening of the suction-controlling valve, a condition of partial vacuum being produced in the chamber, 1, outside the buoy will cause the liquid level to rise outside the buoy and to be depressed inside the buoy until the air escapes around the lower edge of the buoy, passing out from its cavity; and this operation will continue while the liquid flows in through the pipes, 17 and 17^a, until the buoy is lifted and buoyed up against the snap valve action with sufficient force to operate said action and reverse the valves; whereupon the atmospheric pressure operating in the chamber, 1, outside the float will force the liquid which is outside the buoy down, and cause it to rise in the cavity of the buoy, compressing the air which remains therein nearly to atmospheric tension; and the liquid now flowing out of the chamber, 1, into the chamber, 2, and becoming thereby lowered in the chamber, 1, to the lower edge of the buoy, the air will pass around said lower edge and up along the wall thereof through the liquid therein, until the tension inside and outside the buoy is nearly equalized; and the buoy meanwhile falling as the liquid level in the chamber, 1, falls, will eventually operate the snap action and reverse the valves to restore the suction and cut off the atmospheric pressure, and causing a repetition of the action first described. It will be seen that in this operation the air has two opportunities to become charged with gasoline vapor, first in passing from the chamber, 1, outside the buoy, down around the lower edge of the buoy into the cavity thereof, and second, in passing back out of the cavity of the buoy around the lower edge thereof, and up through the liquid in the chamber, 1, outside the buoy to the top of said chamber, with the result above stated, that a large proportion of the

air which is contained in the chamber, 1, above the liquid therein, and subject to the suction for carrying it over into the manifold is adequately enriched with vapor of the gasoline to prevent it from causing any material leanness of the mixture in the engine manifold.

In order that this result may be attained to as high a degree as possible, it is desirable that as large a proportion as possible of the air entering the chamber, 1, should pass into and out of the cavity of the buoy, that is, that the portion of the cavity of the buoy alternately occupied and vacated by the liquid should be as nearly as possible the full air capacity of the chamber, 1, outside the buoy. For this purpose the structure is preferably designed with the buoy only just enough less in diameter than the chamber, 1, to adapt it to move freely up and down therein in the filling and discharging action described.

It will be understood upon careful consideration that upon the reversal of the valves caused by the rising of the float to its high limit and the consequent admission of atmospheric pressure to the chamber, 1, the supply pipe, 17, will empty back into the main low level tank (not shown) and that upon the closing of the atmosphere inlet and the admission of the suction the air in the pipe, 17, 17^a, will be discharged up under the bell float, and thus at each recurrence of the filling action the float cavity will be recharged with atmospheric air; and the tendency to "water logging" will be defeated. But in the absence of means to prevent, the pipe, 17, 17^a, would act as a siphon exhausting from the reservoir, 1, back into the main low level tank a considerable portion of the liquid lifted during the suction period; to prevent this loss without losing the advantage mentioned above, viz: recharging the float cavity with air in each cycle,—the pipe, 17, is provided with an air vent, 17^b, opening into the chamber, 1, at the upper part above the high liquid level of that chamber, which causes the siphon to be broken at that point, so that the liquid in the pipe below that point will fall as the level of liquid in the chamber falls, and the remainder, trapped in the pipe below the low liquid level of the chamber, will be pulled out upon the recurrence of suction, and the air above and behind it will then be drawn for discharge up into the buoy cavity as described.

I claim:

1. In a vacuum fuel feed device comprising a chamber having a liquid fuel supply connection and means for alternating high and low pressure in the chamber, a buoy in the chamber, and connections for operating the pressure-alternating means, said buoy consisting of an inverted cup; the liquid supply connections being positioned for dis-

charging within the cavity of such inverted cup buoy and thereby reaching the remainder of the chamber by passing around the lower margin of the buoy.

- 5 2. In a vacuum fuel feed device comprising a chamber having a liquid fuel supply connection and means for alternating high and low pressure in the chamber, a buoy in the chamber, and connections for operating 10 the pressure-alternating means, said buoy consisting of an inverted cup; the liquid supply connections being positioned for discharge within the cavity of such inverted cup buoy, and said connections being free for 15 return of liquid therethrough toward the source of supply, whereby said connection

becomes occupied by air during the emptying of the chamber and said air is discharged into the buoy cavity on the recurrence of liquid flow to the chamber.

20

3. In a structure such as defined in claim 2, the liquid supply connection having an air vent opening into it leading from the chamber above the high liquid level thereof for breaking at that point the siphon formed by 25 said connection when the same leads from a low level main supply source.

In testimony whereof, I have hereunto set my hand at Chicago, Illinois, this 5th day of July, A. D., 1917.

WEBB JAY.
